UNITED STATES PATENT OFFICE.

JACOB SULZBACH, OF NEW YORK, N. Y.

DESIGN FOR A RIBBON.

51,445.

Specification for Design.

Patented Oct. 30, 1917.

Application filed May 28, 1917. Serial No. 171,331. Term of patent 14 years.

To all whom it may concern:

Be it known that I, JACOB SULZBACH, a citizen of the United States, residing at New York city, in the county of New York and State of New York, have invented a new, original, and ornamental Design for Ribbons, of which the following is a specification, reference being had to the accompanying drawings, forming a part thereof.

The figure is a plan view of a piece of

chromatic ribbon illustrating my new design.

I claim:

The ornamental design for a ribbon, as shown.

JACOB SULZBACH.
